(57) **CLAIM**

The ornamental design for a golf club grip as shown and described.

DESCRIPTION

FIG. 1 is a top, front, right side isometric view of a golf club grip.

FIG. 2 is a top view of the golf club grip of FIG. 1.

FIG. 3 is a bottom view of the golf club grip of FIG. 1.

FIG. 4 is a right side view of the golf club grip of FIG. 1.

FIG. 5 is a left side view of the golf club grip of FIG. 1.

FIG. 6 is a front view of the golf club grip of FIG. 1; and,

FIG. 7 is a rear view of the golf club grip of FIG. 1.

The broken lines show portions of the golf club grip that form no part of the claimed design.

1 Claim, 5 Drawing Sheets
